Patented Nov. 11, 1913.

UNITED STATES PATENT OFFICE.

EDMUND M. CRAWFORD, OF SCHENECTADY, NEW YORK.

LOCOMOTIVE-BELL.

1,078,385.

Specification of Letters Patent.

Patented Nov. 11, 1913.

Application filed June 30, 1913. Serial No. 776,491.

To all whom it may concern:

Be it known that I, EDMUND M. CRAWFORD, of Schenectady, in the county of Schenectady and State of New York, have invented a certain new and useful Improvement in Locomotive-Bells, of which improvement the following is a specification.

The object of my invention is to provide simple and inexpensive means for mounting locomotive bells, particularly on large locomotives, where only a comparatively limited height is available for their installation on the top of the boiler, whereby the total height of the bell and its accessories may be substantially reduced without affecting the tone of the bell or impairing its efficiency as an alarm.

The improvement claimed is hereinafter fully set forth.

20 In the accompanying drawings: Figure 1 is a view, partly in elevation and partly in section, of a locomotive bell and its accessories, embodying my invention, taken in the axial plane of oscillation of the bell; Fig. 2, a partial similar section, illustrating a structural modification of the means for fastening the bell to its shaft; Fig. 3, a transverse section taken at a right angle to Fig. 2; and, Fig. 4, an end view, in elevation, of the bell stand, as seen from the left, showing the operating crank arm and stop spring.

In the practice of my invention, I provide a bell, 1, which, except as hereinafter described, is of the ordinary form. Two oppositely disposed perforations, 1^a, are formed transversely in the bell, through which perforations there extends a supporting shaft, 2, journaled in bearings, 3^a, formed on the tops of the vertically extending members of a bell stand, 3, the base of which is suitably curved to fit on, and be secured to, the top of a locomotive boiler. The shaft, 2, is located in substantially the ordinary manner, relatively to the center of gravity of the oscillating members, such minor change in its location as is made being due to the fact that the bell yoke usually applied, is dispensed with.

50 The bell is interiorly connected to the supporting shaft by an eye bolt, 4, which is preferably, as shown, bifurcated at its lower end and passes through a central perforation in the top of the bell. The forks of the lower end of the eye bolt are perforated to fit truly on the shaft, 2, and the upper end

of the eye bolt is threaded and engaged by a nut, 4^a, and the top of the bell, on which the nut bears, is downwardly recessed, so that the nut does not project to any perceptible extent, above the bell. Recesses, 2^a, are cut in the shaft, 2, on opposite sides of the forks of the eye bolt, and are engaged by lugs, 1^b, which project downwardly from the top of the bell, relative movement of the bell and supporting shaft being thereby prevented. As shown in Fig. 1, the lugs, 1^b, are cast integral with the bell, and as shown in Figs. 2 and 3, they are made as a single separate piece, which may be of cheaper material than the bell, and which is provided with an annular projection, 1^c, fitting around the eye bolt, 4, and in the top of the bell, and secured thereto by the nut, 4^a.

A clapper, 5, is suspended on the supporting shaft, 2, an eye on its upper end fitting in the space between the forks of the eye bolt, and it will be obvious that, if preferred, the upper end of the clapper may be bifurcated, instead of so dividing the eye bolt, 80 this being the mechanical equivalent of the construction shown.

A crank arm, 6, having a pin, 6^a, on its lower end, for the attachment of an operating bell rope, is fixed on one end of the supporting shaft, 2, said crank arm having oppositely disposed lateral wings, 6^b, on its upper end, which are adapted to abut against the upper end of a plate spring, 7, the lower end of which is secured to a lug, 90 3^b, on one of the vertically extending members of the bell stand, 3, and which extends upwardly to within a short distance of the hub of the crank arm, 6. By the bearing of one or the other of the wings, 6^b, against the spring, as the bell reaches its maximum determined traverse or swing in either direction, the bell is prevented from overturning, and its swing is restricted to the desired limit.

100 It will be seen that by the elimination of the usual bell yoke, the weight and the height of the structure are both substantially reduced, the latter reduction being one which is often very desirable in large locomotives of recent construction, and also that the construction is of such character that its several members can be inexpensively manufactured and readily assembled in position for use.

110 I claim as my invention and desire to secure by Letters Patent:

1. The combination of a bell stand, a transversely perforated bell, a supporting shaft journaled in said stand and extending through the bell, a connection extending in the inside of the bell and securing it to the supporting shaft, a clapper journaled on said shaft, and means for oscillating said shaft.
2. The combination of a bell stand, a transversely perforated bell, a supporting shaft journaled in said stand and extending through the bell, a connection extending in the inside of the bell and securing it to the supporting shaft, a clapper journaled on said shaft, means for oscillating said shaft, and means for limiting the degree of oscillation of said shaft.
3. The combination of, a bell stand, a transversely perforated bell, a supporting shaft journaled in said stand and extending through the bell, a bolt having a lower eye fitting on said shaft and attached at its top to the bell, a clapper journaled on said shaft, and means for oscillating said shaft.
4. The combination of a bell stand, a transversely perforated bell having a central recess in its top, a supporting shaft journaled in the bell stand and extending through the bell, a bolt having a lower eye fitting on said shaft and extending through the top of the bell, a nut engaging said bolt and bearing on the recess of the bell, a clapper journaled on the supporting shaft, and means for oscillating said shaft.
5. The combination of a bell stand, a transversely perforated bell, a supporting shaft journaled in said stand and extending through the bell, a bolt having a lower eye fitting on said shaft and attached at its top to the bell, a lug extending from the top of the bell and engaging a recess in said shaft, a clapper journaled on said shaft, and means for oscillating said shaft.
6. The combination of a bell stand, a supporting shaft journaled in said stand, a bell connected to said shaft, a clapper journaled on said shaft, an operating crank arm fixed on said shaft and having oppositely disposed lateral wings, and a vertical plate spring fixed to the bell stand in position to be contacted with by said wings at the extremities of the normal range of oscillation of the crank arm.

EDMUND M. CRAWFORD.
